SANITARY EQUIPMENT CHIEFLY FOR THE
PREPARATION OF CARBONIC GAS BATHS

Pierre Derome, Brussels, Belgium

Application December 15, 1947, Serial No. 791,756
In France December 23, 1946

14 Claims. (Cl. 4—180)

1

It is well known that certain diseases of the circulatory system such as angina pectoris, dys-systolia, hyposystolia, even certain asystoliae, heart arrhythmia, may be successfully treated with baths comprising a high content of carbonic gas dissolved under pressure. Such baths have been demonstrated to be also highly efficient for treating obstructive arteritis, oedema, aerophagy etc. . . . finally such baths have proved highly beneficial to all organisms that have grown aged and weary. By following such a treatment, physical and intellectual ability is recovered and even increased beyond the most hopeful expectations, or in other words they cause an obvious rejuvenation and increase the vitality by cancelling any trace of weariness.

This invention relates to an improved sanitary apparatus which may be arranged in a bathroom and enabling to saturate very quickly the 250 to 300 litres of warm water normally used for a bath, with carbonic gas under pressure, and allowing the patient to prepare the bath by handling himself the control members at hand, above the tub.

According to the invention, an apparatus for preparing baths of water having a high content of carbonic gas, comprises a saturator mixer that receives, on the one hand, water at a suitable temperature flowing from the customary bath taps and, on the other hand, carbonic gas under pressure provided by some convenient supply; the saturator is furnished with means for stirring the water so as to get an even temperature and provision is made for the quick solution of the gas under pressure; there is further an arrangement for running the water from the saturator into the bath while means are provided to direct the fluid stream towards the patient's body, and also means to get rid of the carbonic gas that may escape from the bath water, and finally there is also a device for bringing the pressure down when the saturator is nearly empty so as to avoid any splashing outside the bath.

The control of the emptying of the saturator is combined conveniently with an electric switch that controls the scavenging means of the carbonic gas, so that these various fittings are brought automatically into operation at the moment when the bath starts to run. In addition, the rate of emptying of the saturator may be adjusted by the patient himself when he gets into the bath, so that the speed of flow of the water may be decreased as soon as he enters the bath.

The following disclosure taken with reference to the attached drawings will give a clearer idea of how the invention works while, of course, the

particular points, that will emerge from a study of the drawings and the perusal of the description all come within the scope of the invention. In the drawings:

Figure 1 is an elevational view of the apparatus, the tub over which it is set up being shown in longitudinal section.

Figure 2 is an end view of the same apparatus, the bath appearing in cross-section.

Figure 3 is an elevation of the saturator of which the lower portion is torn off to show the arrangement of the internal fittings.

Figure 4 is an axial section of the water delivery tube opening into the saturator.

Figure 5 is a plan view of the atomizer apparatus for the carbonic gas, a portion of the plugs being stripped off.

Figure 6 is an elevational view corresponding to Figure 5.

Figure 7 is an axial section of the anti-splash tap-nozzle provided at the end of the overflow piping.

Figure 8 is a longitudinal section of the control device of the fan, operated through the handle of the draining tap of the saturator.

Figure 9 is a section through the line IX—IX of Fig. 8.

Figure 10 is an elevation-view of the drain regulator and its control rod provided with a float.

Figure 11 is an axial section of the regulator illustrated in Figure 10.

In the embodiment illustrated in the drawings, the apparatus includes a saturator 1 formed by a tank liable to stand an internal pressure of 7 to 10 kgs. per square centimetre and held above the tub 2 on a suitable support 3 so that the drain pipe 4 of this saturator, located at the centre of its bottom, is placed a short distance above the end of the tub facing the head of the patient.

Water at a suitable temperature is fed to the saturator from the bath taps that may be connected by means of a flexible rubber pipe to a union 5 followed by a check valve 6 fastened on the delivery nozzle 7 opening into the lower portion of the saturator (Figure 3). This delivery nozzle illustrated sectionally in Figure 4 comprises two jet-nozzles; one 7a at right angles to the nozzle collar-nut is slightly inclined on the axis of the saturator and it is directed so as to give an upward stream; the other 7b forms an angle of about 30° with the first one, and it is directed so as to be substantially parallel to the side wall of the saturator, so as to give a whirling effect to the water contained in the apparatus,

thus causing the water to be stirred and the temperature to be uniform. The height of water in the saturator may be ascertained by a gauge not shown that is connected to two pipes 8 and 9.

The upper portion of the saturator is provided with a safety-valve 18 of any standard pattern and an overflow pipe 11 that is attached to the top part of the saturator. Said overflow pipe runs down alongside the latter and ends in an anti-splash tap nozzle 12 formed by a sleeve of large diameter 13 (Fig. 7), surrounding the end of tube 11 to which it is welded and of which the free end 13a presents a wide opening. The end of the overflow pipe 11, that is located inside the sleeve, is plugged and this end of the pipe has a large number of side holes bored through it so that the water coming from the overflow exits as fine sprays impinging on the inner wall of the sleeve and pours out of the latter at a gentle rate.

The patient has within reach a wheel 16 controlling a tap 15 by means of which he may cut off the overflow pipe while the carbonic gas is being dissolved and there is a pressure-gauge 17 provided on tube 11 upstream with respect to the tap 15 so that he may control the pressure inside the apparatus.

On the drain pipe 4 of the saturator is assembled a back-water valve 18 that is actuated by a wheel 19 by means of a long control rod 20 bringing the wheel 19 within reach of the hand of the patient in the bath. Just following the valve 18 there is a drain regulator 21 operated by means of a float lever 22 of which the object is to allow a quick emptying of the saturator into the tub and to slow down the speed of the water flow when the water level in the tub rises sharply as the patient gets into the bath. This adjustment means of the supply of water from the saturator, that is illustrated in Figures 10 and 11, comprises a body 21a provided with a cylindrical chamber 23 in which may turn a throttle valve 24 set on an axle 25 at right angles to the direction of the water flow, and that is actuated by the rod 22 carrying the float 26. The axle 25 is set so that the throttle valve 24 is vertical and leaves the pipe wide open when the float is in its lower position, and it begins reducing the sectional area of the channel for a predetermined water level; an adjustable stop allows the opening to be kept wide open so long as said predetermined water level is not reached.

The drain regulator is connected to a fixed drain pipe 27 provided at its lower part with a hinged joint 28 that allows the terminal pipe 29 to swing vertically.

The end of this pipe is connected by a small chain 30 to the float 26 so that when the water level rises with the patient's entry into the tub, this pipe comes up and directs the water flow towards the front part of the patient's body.

The carbonic gas coming, in a liquid state, from gas tubes is expanded in a standard apparatus to a point where it is at a pressure of about 6 to 7 kg., said apparatus being connected through a suitable piping to the atomiser unit 31. The latter is illustrated on a larger scale in Figures 5 and 6 and includes a collector 31a with three delivery pipes provided at the centre of three cups 32 each carrying a hollow plug 33 of unglazed porcelain. The collector is attached to the saturator by the threaded sleeve 34 and a nut 35 with the insertion of suitable watertight joints.

In order to enable the nozzle 7 and gas-atomiser to be introduced inside the saturator, an

opening of appropriate size has been provided in the wall of the saturator, said opening being obturated by an autoclave-door 36.

In order to sweep away the carbonic gas that is given off from the bath in a large amount, a fan 37 may be made to revolve in a tubular casing 38 of which one end is fitted with an electric resistance 39 that ensures the reheating of the air displaced and the set consisting of fan, casing and resistance may be sloped towards the face of the person in the bath.

Owing to the important amount of gas evolved especially during draining, which may render the air unbreathable, care must be taken, not to enter the bath without having started the fan. In order to prevent any faulty operation, the control of the fan and that of the drain-cock are coupled so that the opening of cock 18 automatically starts the fan 37 and the heating of the resistance 39 at the same time.

To this end, the switch 40 that allows the starting of the fan and energization of the heating resistance (Figures 8 and 9) is set on an iron fitting, integral with the frame supporting the fan unit, and its spindle 41 carries a disc 42 fastened on it, a pulley 43 and another disc 44 both set loose on the spindle. A spring 45 forces the disc 44 and pulley 43 against the disc 42 that has then a friction drive. The switch rotor carries a lug 46 and two stops 47 and 48 integral with the stationary part of the switch frame restrict to half a revolution the rotary motion of the moving part of the switch that makes contact throughout the greater part of its movement. A pulley 49 is keyed on the hand control spindle 20 of the drain-cock 18 and a belt 50 connects the two pulleys 43 and 39. The electrical connections are such that by turning wheel 19 in the direction which causes the drain-cock 18 to open, the pulley 43 turns through $\frac{1}{2}$ a revolution the switch 40 that connects up the fan and resistance on the circuit, thus ensuring the scavenging of any carbonic gas given off, after which the pulley slides over the disc 42 by reason of the gentle thrust of the spring 45. By turning the handle 19 in the opposite direction, the rotation of the switch in the direction of closing of the drain-cock 18, but the electric current is only cut when the contact stud 46 comes close to the upper stop 48 and this allows the flow to be controlled by hand while the contact travels between the two stops without any stoppage of the fan. The gearing down corresponds roughly to the number of turns required to open sufficiently the drain-cock 18 or to decrease its opening as desired.

The apparatus works in the following way: The water supplied by the tub-taps being at the proper temperature which may be ascertained by inserting a thermometer into the union joint 5 (Figure 3), the drain-cock 18 is closed, the overflow tap is open and the saturator is allowed to get filled with water. During the filling, the water is continuously stirred by the two streams 65 coming from jet-nozzles 7a and 7b so that the water is practically uniform in temperature throughout the apparatus. If required, the temperature may be read by means of a thermometer laid inside a tube located half way up the saturator. The filling of the saturator is observed through a water-gauge and when the saturator is completely filled, water starts to flow out through the anti-splash tap-nozzle 12.

The saturator being full of water, the supply taps as well as the overflow-cock 15 are closed,

and the carbonic gas bottle is opened and delivers expanded gas at a pressure between 6 to 7 kg., inside the unglazed porcelain plugs 33 of the atomiser unit 31.

The gas leaves these plugs in the form of minute bubbles, with a considerable dissolving surface, that is in a favourable state for rapid and easy solution. The rise in pressure may be seen in the pressure-gauge 17 and when the pressure inside the saturator is very close to that in the reducing valve the preparation of the gaseous water is complete; the tap of the gas bottle is then closed and the tap 18 for emptying the saturator is at once opened wide. The tub is quickly filled, the regulator 21 being wide open. As soon as the tap 18 is opened, the fan 37 starts up so that the carbonic gas coming off in large amounts is scavenged by the displacement of hot air.

When the water in the tub reaches the level prescribed for each individual, the patient gets into the bath; the water level in the tub naturally rises suddenly and the action of the float 26 on the governor valve slows down the flow of water and raises the pipe 29 that thus directs towards the front of the patient a stream of gaseous water supplied by the saturator. When the latter is nearly empty, as may be seen from the water-gauge that it carries, the pressure is lowered by turning the wheel 16 and thereby opening the tap 15. The water in the overflow pipe 11 is discharged under pressure but any splashing outside the tub is prevented by the anti-splash tap-nozzle 12.

Naturally any suitable modification may be introduced to this type of particular apparatus without departing from the scope of the invention as defined in accompanying claims. For instance, instead of providing a two-way nozzle for the mixing and stirring of the water, a turbine and propeller mixer may be used as illustrated at 51 (Figure 3). This type of mixer that comprises a nozzle 52 directing the stream of feed water on to a paddle wheel 53 with a propeller 54 fixed on top, is fastened inside the saturator on a pipe 8, similar to those provided for the water-gauge, so that the rising flow generated by the turning of the propeller blades is not hindered by the device used for dissolving the gas in the water; for this purpose, the plane of the propeller is conveniently located above the level of the atomiser plugs.

What I claim is:

1. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container, said means including plugs of unglazed porcelain and a manifold collector pipe feeding said plugs with carbonic gas through the container wall; and draining means whereby the container is adapted to empty through its lower end.

2. A sanitary apparatus for the preparation of baths with high contents of carbonic gas adapted to be fitted in a bath-room for association with a bath tub or the like comprising, a mixing and saturating container; means for feeding the container with water at the desired temperature;

means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty through its lower end; means for scavenging the carbonic gas evolved out of the bath water; and by-pass means for reducing the pressure in the saturation vessel including an overflow pipe opening out of the upper part of the saturating container, a tap adapted to close its lower end, and hand operated means for opening said tap to make the pressure drop in the latter when required.

3. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty through its lower end; means for scavenging the carbonic gas evolved out of the bath water; and by-pass means for reducing the pressure in the saturation vessel including an overflow pipe opening out of the upper part of the saturating container, a tap adapted to close its lower end, and hand operated means for opening said tap to make the pressure drop in the latter when required, and an anti-splash nozzle fitted on the lower end of the outerflow pipe.

4. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; and draining means whereby the container is adapted to empty through its lower end including valve means at the lower end of said container, a draining regulator at the outlet of the valve means and a pipe connecting the draining regulator with the lower part of the bath.

5. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; and draining means whereby the container is adapted to empty through its lower end including valve means at the lower end of the container, a draining regulator at the outlet of the valve means and a pipe connecting the draining regulator with the lower part of the bath, a float connected

with said draining regulator and adapted to open wide the regulator for the locations of the float underneath a predetermined water level in the bath and for closing same when the level rises above said predetermined value.

6. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; and draining means whereby the container is adapted to empty through its lower end including valve means at the lower end of the container, a draining regulator at the outlet of the valve means; a pipe connecting the draining regulator with the lower part of the bath; a float connected with said draining regulator and adapted to open wide the regulator for the locations of the float underneath a predetermined water level in the bath and for closing same when the level rises above said predetermined value; and means whereby the float raises the end of the pipe leading to the bottom of the bath for raising same when the level of the water has risen above a predetermined value for directing the stream of incoming water towards the other end of the bath tub.

7. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty through its lower end; means for scavenging the carbonic gas evolved out of the bath water including an electric fan, an electric resistance associated therewith; and means for energizing said fan and resistance.

8. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty through its lower end; means for scavenging the carbonic gas evolved out of the bath water including an electric fan, an electric resistance associated therewith, means for energizing said fan and resistance, a tubular casing enclosing the fan and resistance; and means for angularly shifting said casing in a vertical plane for directing the air blown by the fan towards the end of the bath tub corresponding to the face of the patient.

9. A sanitary apparatus for the preparation of

baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty through its lower end; and means for scavenging the carbonic gas evolved out of the bath water

10 including an electric fan; an electric resistance associated therewith, means for energizing said fan and resistance, a switch controlling the fan, valve means controlling the draining of the saturating container and hand operated means for controlling simultaneously the switch and the valve means.

10. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty through its lower end; means for scavenging the carbonic gas evolved out of the bath water including an electric fan; an electric resistance associated therewith and means for energizing said fan and resistance, a switch controlling the fan, valve means controlling the draining of the saturating container; hand operated means for controlling simultaneously the switch and the valve means.

25 11. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty

30 12 through its lower end; means for scavenging the carbonic gas evolved out of the bath water including an electric fan; an electric resistance associated therewith and means for energizing said fan and resistance, a switch controlling the fan, valve means controlling the draining of the saturating container; hand operated means for controlling simultaneously the switch and the valve means.

35 13 14. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container; draining means whereby the container is adapted to empty

40 15 through its lower end; means for scavenging the carbonic gas evolved out of the bath water including an electric fan; an electric resistance associated therewith and means for energizing said fan and resistance, a switch controlling the fan, valve means controlling the draining of the saturating container; hand operated means for controlling simultaneously the switch and the valve means; by-pass means for reducing the pressure in the saturating container; a draining

45 16 regulator at the outlet of said valve means; a pipe connecting the draining regulator with the lower part of the bath; a float connected with said draining regulator and adapted to open wide the regulator for the locations of the float underneath a predetermined water level in the

50 17 bath and for closing same when the level rises above said predetermined value; and means whereby the float raises the end of the pipe leading to the bottom of the bath when the level of the water has risen above a predetermined value for directing the stream of incoming water towards the other end of the bath tub.

18 19. A sanitary apparatus for the preparation of baths with high contents of carbonic gas adapted to be fitted in a bath-room for association with a bath tub or the like comprising, a mixing and saturating container; means for feeding the container with a mixture of cold and warm water; means for feeding carbonic gas under pressure into the container; means for stirring the mixture of water inside the saturating container for obtaining a uniform temperature therein, said

60 20 means comprising a nozzle located at the bottom of said container, said nozzle having an inlet connected to a pipe providing the mixture of cold and warm water and a pair of outlets angularly sloping for about 30° one with respect to the other, said nozzle being arranged and adapted so

65 21 as to direct inside said container and through

70 22 one of said outlets an upward and substantially

75 23 horizontal stream of air.

vertical stream of water, and through the second outlet an upward stream of water substantially tangential to the vertical wall of said mixing container; means for furthering the thorough dissolution of the carbonic gas in the water inside the container; and draining means whereby said container is adapted to empty through its lower end.

12. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container, said means including plugs of unglazed porcelain and a manifold collector pipe feeding said plugs with carbonic gas through the container wall; draining means whereby said container is adapted to empty through its lower end; and means automatically moderating the rate of flow of the carbonated warm water out of the container into said bath tub when the patient enters the bath.

13. A sanitary apparatus for the preparation of baths with high contents of carbonic gas adapted to be fitted in a bath-room for association with a bath tub or the like comprising, a mixing and saturating container; means for feeding the container with water at the desired temperature; means for feeding carbonic gas under pressure into the container; means for stirring the water inside the saturating container for obtaining a uniform temperature therein; means for furthering the thorough dissolution of the carbonic gas in the water inside the container, said means including plugs of unglazed porcelain and a manifold collector pipe feeding said plugs with

carbonic gas through the container wall; draining means whereby said container is adapted to empty through its lower end; and means for automatically tilting upward the stream of carbonated warm water flowing into said bath tub and directing said stream towards the front of the patient's body when he enters the bath.

14. A sanitary apparatus for the preparation of baths with high contents of carbonic gas adapted to be fitted in a bath-room for association with a bath tub or the like comprising a mixing and saturating container, means for feeding the container with water at the desired temperature, means for feeding carbonic gas under pressure into the container, means for stirring the water inside the saturating container for obtaining a uniform temperature therein, means for furthering the thorough dissolution of the carbonic gas in the water inside the container, draining means whereby the container is adapted to empty through its lower end; means for blowing out of said bath tub the carbonic gas evolved from the bath water; and by-pass means for reducing the pressure in said saturating container.
